US00D579160S

(12) **United States Design Patent**
Lebot et al.

(10) **Patent No.:** **US D579,160 S**
(45) **Date of Patent:** **** Oct. 21, 2008**

(54) **STEAM GENERATING BASE FOR A
LAUNDRY IRON**

(75) Inventors: **Laurent Lebot**, Nantes (FR); **Victor
Massip**, Nantes (FR)

(73) Assignee: **Calor**, Lyons (FR)

(**) Term: **14 Years**

(21) Appl. No.: **29/278,247**

(22) Filed: **Mar. 23, 2007**

(30) **Foreign Application Priority Data**

Oct. 10, 2006 (FR) 06 4585

(51) **LOC (8) Cl.** **15-05**

(52) **U.S. Cl.** **D32/9**

(58) **Field of Classification Search** D32/9,
D32/68-73, 17-18, 21, 23-24, 31-33; 68/5 R,
68/222, 5 A; 38/85, 82, 77.8, 81, 94, 77.83,
38/79, 96; 392/405, 324, 333, 342, 379,
392/403; 219/259, 242, 254, 246; 8/149.3;
15/344, 329, 320-322, 415.1-422.1, 327.1-327.2,
15/327.6-627.7

See application file for complete search history.

(57) **CLAIM**

The ornamental design for a steam generating base for a laundry iron, as shown and described.

DESCRIPTION

FIG. 1 is a front, top, right perspective view of a steam generating base for a laundry iron, showing our design;

FIG. 2 is a rear, top, left perspective view thereof;

FIG. 3 is a left view thereof;

FIG. 4 is a right view thereof;

FIG. 5 is a front view thereof;

FIG. 6 is a rear view thereof;

FIG. 7 is a top view thereof; and,

FIG. 8 is a bottom view thereof.

1 Claim, 8 Drawing Sheets
